A technical drawing showing a cross-section of a mechanical assembly. It features a central vertical column with a horizontal top plate. A horizontal beam is attached to the top plate. The assembly is labeled with several dimensions: '36a' is on the left side of the vertical column, '34a' is on the right side of the top plate, '29a' is on the right side of the horizontal beam, and '32a' is on the right side of the bottom horizontal plate. The drawing uses lines and hatching to indicate different parts and their relative positions.

UNITED STATES PATENT OFFICE.

LOUIS T. HAGAN, OF WINCHESTER, KENTUCKY.

BELT-SHIFTER.

1,160,881.

Specification of Letters Patent.

Patented Nov. 16, 1915.

Application filed November 4, 1914. Serial No. 870,273.

To all whom it may concern:

Be it known that I, LOUIS T. HAGAN, a citizen of the United States, residing at Winchester, in the county of Clark and State of Kentucky, have invented new and useful Improvements in Belt-Shifters, of which the following is a specification.

My present invention relates to improvements in belt shifters of the type adapted to shift belts between stepped cone pulleys, and the primary object of the invention is to provide novel, improved and relatively simple means for accomplishing this result quickly and with facility. It is an improvement upon the belt shifter shown and described in my prior Patent, No. 1,036,487, granted August 20, 1912.

To these and other ends, the invention consists in certain improvements, and combinations and arrangements of parts, all as will be hereinafter more fully described, the novel features being pointed out particularly in the claims at the end of the specification.

In the accompanying drawings:—Figure 1 is a front elevation of a portion of a machine equipped with belt shifting mechanism constructed in accordance with the present invention; Fig. 2 is a view of the same as it appears from the left in Fig. 1; Fig. 3 represents a transverse horizontal section on the line 3—3 of Fig. 1; Fig. 4 represents a transverse section on the line 4—4 of Fig. 3; Fig. 5 is a detail front elevation of the belt shifter; Fig. 6 shows the same as viewed from the left in Fig. 5; Fig. 7 represents a section on the line 7—7 of Fig. 3 with parts removed; Fig. 8 is a detail sectional view showing the operating shaft; Fig. 9 is a view similar to Fig. 1 showing another embodiment of the invention; Fig. 10 is an elevation of the construction shown in Fig. 9 as viewed from the left; Fig. 11 represents a transverse section on the line 11—11, Fig. 9; Fig. 12 is a front elevation of the belt shifter shown in Figs. 9 to 11 inclusive; Fig. 13 represents a section on the line 13—13 of Fig. 11; Fig. 14 represents a section on the line 14—14 of Fig. 11; Fig. 15 is a detail view, similar to Fig. 8, showing a modified construction employing a pair of rack plates.

Similar parts are designated by the same reference characters in the several views.

Belt shifters embodying the present invention are capable of use generally in con-

nexion with machinery of various kinds employing stepped cone pulleys. In the accompanying drawings the preferred embodiments of the invention are shown, but it is to be understood that the invention is not restricted to the precise constructions shown, as equivalent constructions operating upon the same principle and capable of accomplishing the same result are contemplated and intended to be covered by the claims at the end of the specification.

In the present instance 1 designates a standard, 2 and 3 shafts carrying stepped cone pulleys 4 and 5, power being transmitted to the shaft 3 in the present instance by the pulleys 6 and transmitted at the different desired speeds to the shaft 2 by the belt 7 passing over the pulleys 4 and 5.

According to the present invention means is provided for shifting the belt 7 in either direction axially of the cone pulleys 4 and 5 whereby different speed ratios may be obtained between the shafts 2 and 3, and the present invention enables this result to be accomplished by simple and improved mechanism which can be conveniently located at a point intermediate the cone pulleys. In the construction shown in Figs. 1 to 8 inclusive, a frame is fixed to the standard 1, the frame comprising a pair of rods 8 and 9 which are connected at their ends by the cross members 10 and 11, the cross member 11 being bolted or otherwise secured in fixed position on the standard 1. A pair of belt guides 12 and 13 are employed, these belt guides being arranged to coöperate with the belt 7 in proximity to the points where the belt passes upon the pulleys 4 and 5 respectively. The belt guide 12 is fixed to a clamp 14 which latter is clamped at the proper point longitudinally of a sleeve 15, the sleeve 15 being slidable longitudinally on the rod 8. The other belt guide 13 is secured by a clamp 16 to a sleeve 17 which is slidable longitudinally on the rod 9. A collar 18 is attached to one end of the sleeve 17 by a pin 19 which maintains the collar 18 in proper longitudinal position on the sleeve 17 but permits the necessary degree of rotation of the sleeve 17 on the rod 9 to allow the belt shifter 13 to swing toward or from its respective cone pulley according to which section of the cone pulley the belt engages. The collar 18 has a bracket 20 fixed thereto and the bracket is provided with a vertical slot 21. A collar 22 similar

to the collar 18 is fixed to the sleeve 15 and permits the necessary rotation of said sleeve whereby the belt shifter 12 may adjust itself according to which particular section of the respective cone pulley is engaged by the belt. A bracket 23 is fixed to the collar 22 and provided with a vertical slot 24. A frame 25 spans the rods 8 and 9 and has bearings 26 and 27 which are slideable longitudinally on said rods. This frame 25 also has an extended bearing 28 which is slideable longitudinally on the sleeve 17. An operating shaft 29 is journaled in the frame 25 and is provided at one end with a crank disk 30 having a pair of pins 31 and 32 projecting from the face thereof while the opposite end of the shaft 29 is provided with a crank 33 having a crank pin 34. The crank pin 34 operates in the vertical slot 24 of the bracket 23 while the pin 32, on the disk 30, which is longer than the pin 31, operates in the vertical slot 21 of the bracket 20. An operating handle is slideably connected to the shaft 29. In the present instance the handle 35 is connected to an extension of the crank pin 32. A toothed bar or rack 36 is secured in fixed relation to the frame composed of the rods 8 and 9 and cross members 10 and 11, it being secured in the present instance to arms 37 and 38 which are extended from the cross members 10 and 11, and this toothed bar or rack is formed with longitudinally spaced slots or recesses 39 which are adapted to receive the pins 31 and 32 on the disk 30 as the shaft 29 is rotated.

In operation, one revolution of the crank 35 and the shaft 29 to which it is connected serves to shift the belt from one section of the stepped cone pulley to the next adjacent step, and this is accomplished in such a way that the belt is first shifted from a section of larger diameter to one of smaller diameter on the appropriate pulley and the belt is afterward shifted from the section of smaller diameter to the next section of larger diameter on the other cone pulley. For example, in order to shift the belt to the left one step the crank 35 is turned one revolution in a left-hand direction. During the first half revolution of the crank, the crank pin 32 works idly in a slot of the toothed bar 36 and the slot 21 of the bracket 20 and, consequently, the belt shifter 13 will remain stationary but the crank pin 34 will operate in the slot 24 of the bracket 23 and will shift the belt guide 12 to which it is connected one step to the left, thereby transferring the belt from a section of larger diameter to the next section of smaller diameter to the left on the pulley 4. When the first half revolution of the shaft 29 is completed, continued rotation of the shaft causes the crank pin 31 to leave one slot in the toothed bar 36 to pass over the shaft 29 and engage a slot in the bar 36 beyond that engaged by

the pin 32, and during this movement the bracket 20 engaged by the pin 32 will be shifted one step toward the left, carrying with it the belt guide 13 to which it is connected, thereby transferring the belt from a section of smaller diameter to the next adjacent one of larger diameter on the pulley 5, the belt guide 12 remaining stationary during the shifting of the belt guide 13. In this manner, the belt can be shifted to any desired position to the left by turning the crank 35 in a left-hand direction, and to any position to the right by rotating the crank 35 in a reverse or right-hand direction. Instead of using a single rack bar, a pair of rack bars 36^a and 36^b may be used, as shown in Fig. 15, the shaft 29^a having its crank pins 32^a and 34^a set in diametrically opposite relation and alternately engaging the respective rack bars.

In the construction shown in Figs. 9 to 14 inclusive, another embodiment of the invention is shown applied to a structure similar to that shown in Figs. 1 to 8 inclusive. In this instance, a frame is provided which embodies a pair of guide bars 40 and 41 which are connected by the cross members 42 and 43, the cross member 43 being fixed to the standard 1 at a point between the stepped cone pulleys 4 and 5. A pair of upper and lower belt guides 44 and 45 are provided which are similar to the belt guides 12 and 13, these belt guides being fixed upon rods 46 and 47. A pair of slides 48 and 49 are mounted longitudinally on the bars 40 and 41 and support and are operatively connected to the rods 46 and 47. The slide 48 is formed with a slot 50 and the slide 49 with a slot 51. A frame 52 is guided to move freely in a longitudinal direction relatively to the bars 40 and 41 and supports an operating shaft 53, the latter having a crank 54 at one end provided with a crank pin 55 which operates in the slot 50 of the slide 48, and a disk 56 is fixed to the opposite end of the shaft 53 and is provided with a pair of pins 57 and 58 adapted to coöperate with a series of longitudinally spaced slots 59 formed in a toothed bar or rack 60 which latter is secured to the bar 41. The pin 58 also operates in the slot 51 of the slide 49, the pin 57 being shorter and operating only in the slots or notches of the rack 60. An operating handle similar to the handle 35 may be fixed to the pin 58. The mode of operation of the construction shown in Figs. 9 to 14 inclusive is similar to that described in connection with the previous construction, the belt guides 44 and 45 being alternately shifted one step, either to the right or to the left, according to the direction of the operating shaft, and causing the belt to be first transferred from a section of larger diameter to one of smaller diameter on one cone pulley and subse-

quently transferred from a cone section of smaller diameter to the next one of larger diameter on the other cone pulley.

The present invention provides a belt shifter which enables a belt to be shifted quickly and with certainty on stepped cone pulleys, and the construction is relatively simple and capable of being applied easily to a machine, and when applied it is compact and in a position where it will not interfere with other parts of the machine or with the manipulation thereof.

I claim as my invention:—

1. In a belt shifter, the combination with a pair of stepped cone pulleys, and a belt coöperative therewith, of a pair of belt shifting guides for the respective pulleys, a frame located between the pulleys, slides movable on said frame and operatively connected to the respective belt guides, a rack bar, and an operating shaft operatively connected to the respective slides and coöperative with said rack bar to alternately shift the belt guides in the same direction, the movement of one guide being in advance of the movement of the other guide.

2. In a belt shifter, the combination with a pair of stepped cone pulleys, and a belt coöperative therewith, of a pair of belt shifting guides for the respective pulleys, a frame located between the pulleys, slides movable on said frame and operatively connected to the respective belt guides, a rack bar, a member reciprocable on said frame, an operating shaft supported by said member and operatively connected to the respective slides and coöperative with said rack bar to alternately shift the belt guides in the same direction.

40 3. In a belt shifter, the combination with a pair of stepped cone pulleys, and a belt coöperative therewith, of a pair of belt shifting guides for the respective pulleys, a frame located between the pulleys, slides movable on said frame and operatively connected to the respective belt guides, a rack bar, and an operating shaft having a crank

coöperative with one of said slides, and another crank having a pair of pins both of which coöperate with the rack bar and one of which coöperates with the other slide.

4. In a belt shifter, the combination with a pair of stepped cone pulleys, and a belt coöperative therewith, of a pair of belt shifting guides for the respective pulleys, a frame located between the pulleys, slides movable on said frame and operatively connected to the respective belt guides, said slides having slotted portions connected thereto, a rack bar, and an operating shaft having a crank coöperative with the slotted portion of one slide and a pair of crank pins, one pin coöperating with the slotted portion of the other slide and also with the rack, and the other pin coöperative with the rack.

5. In a belt shifter, the combination with a pair of stepped cone pulleys, and a belt connecting them, of a pair of belt shifting guides for said pulleys, a supporting frame, a pair of slides reciprocable on the frame and pivotally supporting the belt guides to swing toward and from the respective pulleys, and means connected to said slides for shifting them.

6. In a belt shifter, the combination with a pair of stepped cone pulleys, and a belt coöperative therewith, of a pair of belt shifting guides for the respective pulleys, a frame having slides movable thereon and operatively connected to the respective belt guides, an operating shaft connected to the respective slides, and rack means coöperative with said shaft for causing alternate shifting of the belt guides in the same direction and one in advance of the other.

In testimony whereof I have hereunto set my hand in presence of two subscribing witnesses.

LOUIS T. HAGAN.
